UNITED STATES PATENT OFFICE.

JOSEPH A. WALSH, OF PHILADELPHIA, PENNSYLVANIA.

PROJECTILE.

1,302,996.

Specification of Letters Patent.

Patented May 6, 1919.

Application filed March 27, 1918, Serial No. 224,928. Renewed March 5, 1919. Serial No. 280,862.

To all whom it may concern:

Be it known that I, JOSEPH A. WALSH, a citizen of the United States, residing at Philadelphia, in the State of Pennsylvania, have invented a certain new and useful Improvement in Projectiles, whereof the following is a specification, reference being had to the accompanying drawings.

My invention relates to mechanically operative means for causing the explosion of a projectile at a predetermined time, prior to its encountering any obstacle, but includes means for insuring its explosion, by percussion, upon encountering any obstacle prior to such predetermined time.

As hereinafter described, my invention includes adjustably variable, mechanically operative, time fuse mechanism, including a rotary screw shaft, extending axially with respect to the projectile, but mounted in a separable fuse casing at the forward end of the projectile and arranged to be rotated by a pneumatic vane at the forward end of the projectile, carried by a countershaft connected with said screw shaft by suitable gearing; said screw shaft carrying a nut which is caused to move forwardly thereon by the rotation of said shaft with respect to the projectile; said nut carrying a material capable of producing sparks, ignitable by friction and arranged to be scratched by a striker wheel. Said striker wheel is keyed upon a shaft extending parallel with said screw shaft in said casing and arranged to be rotated by a pneumatic vane at the forward end thereof; said striker wheel being mounted in a carriage which, when adjusted, is held in such position, longitudinally with respect to the projectile and said screw shaft, as to predetermine the point at which said sparking material shall be scratched and, consequently, the time of explosion. Said carriage has a serrated face complementary to a serrated face of a timing scale plate in said casing, and clamping means are provided for holding said carriage on said scale plate in any position throughout its range of adjustment so that said carriage may be longitudinally adjusted with respect to said casing, and said screw shaft, the shortest variation in its position being the extent of one of said serrations. However, said scale plate is provided with micrometer adjusting means for precisely adjusting it longitudinally in said casing, fractional parts of the extent of one

of said serrations; such adjusting means being graduated to one hundredths of a serration.

My invention includes, as an adjunct to the mechanical time fuse mechanism above contemplated, a percussion fuse mechanism, arranged to operate only when the projectile encounters an obstacle, and including a plunger cartridge containing an element of pyrographic alloy, or other igniting material, mounted to slide longitudinally in said casing upon a support having means to scratch and ignite it. Conveniently, such support is a rod having a surface which is file cut or otherwise roughened, and the cartridge includes a priming charge of explosive; so that the latter may be ignited by the sparks produced by the longitudinal movement of the igniting material upon said rod, and thus effect the desired explosion of the projectile.

Although I prefer to employ what is termed a "pyrographic" or "pyrophoric" alloy, for instance a composition of 65 per cent. cerium earth metals and 35 per cent. iron, as the igniting material; I do not desire to limit all of my claims to such material. However, the adaptation of my present invention to the use of a pyrographic alloy is of great importance in the present state of war, not only because of the constant danger of accidental ignition of all fulminating materials ordinarily employed, but because they require a long time for their proper preparation for use, as, after ordinary fulminating devices are mechanically completed, they must be subjected to a prolonged baking process to insure their proper operation; whereas, when my improved device is completed mechanically, it is ready for instant use.

My invention includes the various novel features of construction and arrangement of such a friction, time, and percussion fuse hereinafter more definitely specified.

In the drawings: Figure I is a front end elevation of a structure conveniently embodying my invention, and including a moisture proof cap which is employed merely to prevent damage to such structure during its storage or transportation but which is removable and is removed before the projectile is fired.

Fig. II is a side elevation of said structure.

Fig. III is a front end elevation of said

structure, with the moisture proof cap removed.

Fig. IV is a side elevation of said structure, as shown in Fig. III, with the shield 5 turned to expose the variable timing mechanism.

Fig. V is a longitudinal sectional view of said structure, taken on the line V, V in Fig. IV.

10 Fig. VI is a rear end elevation of said structure, as shown in Fig. V.

Fig. VII is a longitudinal, sectional view of said structure taken on the line VII, VII in Figs. III and V.

15 Fig. VIII is a transverse, sectional view, taken on the line VIII, VIII in Figs. IV and V.

Fig. IX is a fragmentary, perspective view of the lower end of the timing scale 20 shown in section in Fig. V.

Fig. X is a transverse, sectional view of the structure shown in Fig. VIII, but showing the coöperative relation of the firing mechanism.

25 Fig. XI is a front end elevation of a modified form of my invention, wherein worm gearing is substituted for the spur gearing shown in Fig. V, connecting the screw shaft with the vane which drives it.

30 Fig. XII is a longitudinal sectional view of the modified form of my invention shown in Fig. X.

Fig. XIII is a perspective view of the nut which travels on said screw shaft; 35 showing the arrangement of the chamber for a priming charge therein.

Fig. XIV is a perspective view of the firing train shown in cross section in Fig. VIII.

40 In said figures; the casing 1 is attached to the forward end of the projectile 2 by the screw thread 3. Said casing is conveniently formed of a body portion 5, preferably of nonmetallic material, having the caps 6 and

45 7 respectively at the front and rear ends thereof and secured in rigid relation therewith by the rivets 4 or screws 8. The screw shaft 9 is journaled in said caps 6 and 7, as shown in Figs. V and VII and provided

50 with the gear wheel 10 in engagement with the gear wheel 11 on the driving shaft 12 provided with the pneumatic vane 13 by which said shaft 12 is rotated relatively to the projectile 2; the latter having a right hand rotation imparted to it by the rifling in the barrel from which it is projected.

Of course, if said shaft 12 were not capable of rotating in the casing 1, relatively to the projectile, it would be rotated by and

60 with the projectile at the rate of rotation of the latter, due to the rifling aforesaid, which is usually such that the projectile makes one complete revolution during its movement to the extent of thirty-five times its diameter, 65 and, if said shaft 12 is held stationary by

the pressure of the air in front of the projectile, the relative rotation of said shaft 12 and of the screw shaft 9, with respect to the projectile, would be determined by the actual rotation of the projectile, and the ratio of 70 the gears 10 and 11; whereby said screw shaft 9 may be caused to rotate at any desired speed to carry forward in the casing 1 the nut 14 with which it is engaged, as shown in Figs. V and VII.

75

Said nut 14 has an undercut recess 15 in which the sparking elements 16 are mounted, as best shown in Fig. XIII, so as to afford a pocket 17 between them for explosive material which is in communication with the 80 chamber 19 extending transversely in said nut, near the bottom thereof, as shown in Figs. X and XIII. Said elements 16 are caused to spark by the scraping action of the striker wheel 20 when said nut is carried 85 forward, by the rotation of said shaft 9, to the position where said wheel 20 has been set with reference to the length of said casing 1. Said wheel 20 is keyed to slide axially

90

upon, but is rotated by, the shaft 21, which is journaled in said caps 6 and 7 and has the collar 22 to prevent its axial displacement, as shown in Fig. V. Said striker wheel shaft 21 is provided at its forward end with the pneumatic vane 24, which is operated in 95 the same way as the vane 13 above described; said vanes 13 and 24 being respectively disposed in the cup-shaped recesses 25 and 26 in said cap 6. In order to adjustably vary the position of said striker wheel 20, and 100 consequently vary the time at which the projectile shall be exploded, I mount said wheel in the carriage 28 which has a serrated face 29 complementary to the serrated face 30 of the timing scale frame 31 which has the 105 slot 32 through which the clamp screw 33 of said carriage extends for engagement with the nut 35 on the outer face of said frame; whereby said carriage may be held in rigid 110 relation with said frame 31 but is adjustable 115 longitudinally with respect to said screw shaft 9, the shortest variation in its position being the extent of one of the serrations of said faces 29 and 30, conveniently one twentieth of an inch. However, said frame 31 is provided with micrometer adjusting means for precisely adjusting it longitudinally in said casing 1, fractional parts of the extent of one of said serrations, including the screw 37 at its inner end, which is ad- 120 justably fitted in said cap 7 and has the milled flange 38 by which it may be turned, and the stud 39 journaled in the bearing 40 of said frame shown in Figs. V and IX.

Said carriage 28 is provided with the in- 125 dex pointer 42, which is rigidly connected therewith, so as to project through the slot 32 in said frame 31, in coöperative relation with the timing scale 45 which is a longi- 130 tudinal series of graduations on said frame

31, as shown in Fig. IV. Each of said graduations conveniently represents the longitudinal traverse of the nut 14, consequent upon one relative rotation of the screw shaft 5 9; whereby the device may be adjustably set to effect the desired explosion of the projectile after a predetermined number of revolutions of the latter.

The construction and arrangement above 10 described are such that when the sparking elements 16 are struck by said wheel 20, which is being constantly rotated during the traverse of the projectile, the explosive material in the pocket 17 and chamber 19 is discharged so as to ignite the firing train 47, 15 opposed thereto as shown in Fig. X. Said firing train conveniently includes a strip of explosive material upon a sheet metal plate 48 having a flap 49 which is normally closed 20 upon it as shown in Figs. VIII and XIV, and may be sealed with wax, in its closed position, but is provided with the chain 50, extending from said flap 49 through the hole 51 in said frame 31 and having a ball handle 25 52 at its outer end, as shown in Figs. IV and XIV; whereby the outer flap cover 49 of said firing train forms a safety cover normally sealing the explosive material 47 on said plate 48 and preventing communication be- 30 tween said igniting device and said firing train and between said firing train and the explosive charge, but which may be opened to the position shown in Fig. X when it is desired to discharge the projectile. I find it 35 convenient to prevent accidental displacement of said firing train plate 48 by providing it with opposite end flanges 55 and 56 as shown in Fig. XIV. Said flange 55 extends between said body 5 and the cap 6, in en- 40 gagement with one of said screws 8, and said flange 56 extends between body 5 and cap 7 in engagement with one of said screws 8.

Said firing train strip 47 may be conveniently formed by coating said plate 48 with 45 a mixture of gun powder, shellac and alcohol, and I prefer to make said plate 48 of lead which is pressed in a die so as to form a series of staggered ribs 58 thereon, as indicated in Fig. XIV, so as to support said 50 strip 47 more securely than if it were applied to a smooth surface.

As an adjunct to the friction, time fuse mechanism above described; I prefer to provide said casing 1 with percussion fuse 55 mechanism comprising the cylindrical cartridge 60, shown in Fig. VII, including an outer casing of sheet metal containing rings 61 of sparking material with alternate sleeves 63 of explosive material. Said plunger is 60 mounted upon the rod 65 which is held at its opposite ends in said caps 6 and 7, and has its forward portions 66 file cut or knurled to scratch said sparking material 61 when the plunger is thrown forward by the im- 65 pact of the projectile, and thus explode said

sleeves 63. However, in order to prevent accidental forward movement of said plunger 60; I find it convenient to provide it with an annular groove at its rear end, primarily engaging projections 68 on a disk which is seated in the recess 69 in said head 7, as shown in Fig. VII. It is to be understood that when said projectile 2 is fired, the initial stress is such as to throw said plunger 60 rearwardly to break its connection with said disk 68; so that, thereafter, it is free to slide forward upon said rod 65 when the projectile strikes some other object.

In order that the fuse mechanism above described may be effective to explode the 80 main charge of the projectile 2; I provide the cap 7 with the priming charge 70 of explosive in the shell 71 which is tightly fitted in the recess 72 and has the two passageways 73 and 74 through which said charge 70 may 85 be ignited respectively by the flash from said time fuse firing train or by the flash from said percussion fuse plunger 60. That is to say; the time fuse mechanism above described may be set to effect the explosion of 90 the projectile after a predetermined number of revolutions of the latter, and consequently at a predetermined distance from the gun by which the projectile is fired; but, said fuse mechanism includes percussive means to ef- 95 fect the explosion of the projectile if it encounters an object before it has traversed the distance for which the time fuse mechanism has been set.

Although said nut 14 can only be thrust 100 forwardly into firing position by rotation of the screw shaft 9; I prefer to seal it in its initial position shown in Figs. V and VII, by a capsule of paper or other frangible material 75, having its rear edge engaged 105 between said body 5 and cap 7. However, upon rotation of said screw shaft, said capsule is broken by the consequent forward movement of said nut 14; leaving the ruptured capsule in the position shown.

The form of my invention shown in Figs. XI and XII is similar to that above described, but includes worm gearing in lieu of said spur gears 10 and 11, in order to afford a longer range of adjustment of the 115 time fuse mechanism. In said figures; the vane 76 is carried by the shaft 77 having the worm 78 engaging the worm gear 79 on the shaft 81 having the worm 82 engaging the worm gear 83 on the screw shaft 84, which otherwise is constructed and arranged like the screw shaft 9 so that relative rotation of said vane 76 causes much slower rotation of the screw shaft 84 than is effected by the spur gearing aforesaid.

I also prefer to protect the timing mechanism above described by a cylindrical, tubular shield 86, fitted to turn upon said body 5 and having the opening 87, which may be turned to expose the timing mech- 125 130

anism as shown in Fig. IV; such turning movement being limited by the pin 89 projecting from said body 5. Said body 5 is also preferably provided with packing bands 6 90 and 91, respectively at its forward and rear ends, sealing the space between said body and said shield 86; and said body is also provided with the packing strip 93, shown in Figs. IV and VIII, sealing the 10 edge of the opening 87 when said shield 86 is turned to cover the timing mechanism which is exposed in Fig. IV. It may be observed that the rotary motion of the projectile tends to close said shield and keep 15 it closed.

The structures above described are operated as follows: The range of the proposed trajectory of the projectile being predetermined; the length of the screw shaft 20 from the forward end of the nut which traverses it represents the total extent of the proposed trajectory and the time of explosion of the projectile may be predetermined, with reference to the length of said trajectory, by adjusting the carriage 28 on the frame 31 and the micrometer screw 37 accordingly. Whereupon, when the projectile reaches the point in its trajectory predetermined as the point of explosion, the front 30 edge of the sparking elements 16 reach the scratching edge of the striker wheel 20 thus discharging the primary charge 70 into the main charge of explosive in the projectile and exploding the latter. However, if said 35 projectile encounters an obstacle prior to the point of explosion, predetermined as aforesaid, it will be discharged by the consequent forward movement of the cartridge 60 bringing the element 61 into percussive 40 contact with the scratching surface 66 of the rod 65; thus discharging the explosive 63 into communication with said priming charge 70.

When said body 5 is made of comparatively soft material, such as wood or vulcanized fiber, I prefer to provide the central cavity thereof with a metallic lining 94, to lessen the friction of the nut 14 upon the wall of said cavity; such friction being 50 incident to the tendency of said nut to turn during its longitudinal traverse upon the screw 9.

As it has been found in practice that the screws exposed to the impact of the atmosphere upon projectiles traveling at high velocity are retracted from their sockets, presumably by pneumatic pressure, I prefer to provide the head 6, the sockets in said head in which the screws 8 are seated, as indicated in Figs. 55 III and IV.

In order to protect from accidental displacement, the fuse mechanism above described; I prefer to provide the casing 1 65 with a water-proof cap 95 which has a screw

thread fitted to the screw thread 96 on the head 7 of said casing; so that, when packed for transportation, the mechanism is fully protected as indicated in Figs. I and II. Of course, such caps are removed before 70 the projectiles are fired.

I do not desire to limit myself to the precise details of construction and arrangement herein set forth, as it is obvious that various modifications may be made therein 75 without departing from the essential features of my invention as defined in the appended claims.

I claim:

1. In a projectile, a fuse casing comprising a body portion of nonmetallic material, having a recess; metallic caps respectively at the front and rear of said body; a tubular, metal shield encircling said body, between said caps, having an opening adapted to register with said recess, but rotatable on said body to close said recess; time fuse mechanism in said casing including two shafts, parallel with the axis of the projectile, each having means at the front end thereof whereby it may be independently pneumatically rotated; one of said shafts being screw threaded; a nut on said screw shaft; means preventing the rotation of said nut; an element of pyrographic alloy carried by said nut; a rotary striker wheel carried by said other shaft, in position to scratch said alloy when the latter is presented thereto by the traverse of said nut on said screw shaft; whereby sparks are produced by the engagement of said wheel and alloy; a firing train arranged to be ignited by such sparks, including a trough shaped metal holder, extending parallel with said shafts and carrying a strip of combustible material upon its face toward said wheel; a priming charge of explosive at the rear end of said firing train, arranged to explode the projectile; means whereby the position of said wheel may be variably adjusted, including a timing scale frame, mounted in said body, parallel with said shafts, and having a slot, a series of serrations, and means for adjusting said frame longitudinally in said casing, including a screw at one end thereof; a carriage for said wheel mounted to slide axially upon its shaft, having serrations complementary to the serrations on said frame, and a screw threaded shank extending through said slot; and a nut, whereby said carriage may be clamped in different positions of adjustment on said frame, to variably determine the point in the traverse of said nut where it shall be engaged by said wheel; percussion fuse mechanism 115 including a rod, parallel with the axis of the projectile, having one portion smooth and another portion roughened; a cartridge mounted on the smooth portion of said rod, but adapted to slide upon the rough portion 120 125 130

of said rod, including an outer metallic shell inclosing an element of pyrographic alloy, and an explosive element arranged to be ignited by sparks from such alloy; and

5 means in said casing normally detaining said cartridge upon the smooth portion of said rod, including a frangible projection in said casing engaging the shell of said cartridge; and means whereby said cartridge is

10 in communication with said priming charge and adapted to explode it.

2. In a projectile, a fuse casing comprising a body portion, having a recess; caps respectively at the front and rear of said body; a tubular, shield encircling said body, between said caps, having an opening adapted to register with said recess, but rotatable on said body to close said recess; time fuse mechanism in said casing including two

15 shafts, parallel with the axis of the projectile, having means at the front end thereof whereby they may be pneumatically rotated; one of said shafts being screw threaded; a nut on said screw shaft; means

20 preventing the rotation of said nut; an element of pyrographic alloy carried by said nut; a rotary striker wheel carried by said other shaft, in position to scratch said alloy when the latter is presented thereto by the

25 traverse of said nut on said screw shaft; whereby sparks are produced by the engagement of said wheel and alloy; a firing train arranged to be ignited by such sparks, including a holder carrying a strip of combustible material upon its face toward said wheel; a priming charge of explosive at the

30 rear end of said firing train, arranged to explode the projectile; means whereby the position of said wheel may be variably ad-

35 justed, including a timing scale frame, mounted in said body, parallel with said shafts, and having a slot, a series of serrations, and means for adjusting said frame longitudinally in said casing, including a

40 screw at one end thereof; a carriage for said wheel mounted to slide axially upon its shaft, having serrations complementary to the serrations on said frame, and a screw threaded shank extending through said slot,

45 and a nut, whereby said carriage may be clamped in different positions of adjustment on said frame, to variably determine the point in the traverse of said nut where it shall be engaged by said wheel; percussion

50 fuse mechanism including a rod, parallel with the axis of the projectile, having one portion smooth and another portion roughened; a cartridge mounted on the smooth portion of said rod, but adapted to slide

55 upon the rough portion of said rod, includ-

60 ing an element of pyrographic alloy, and an explosive element arranged to be ignited by sparks from such alloy; frangible means in said casing normally detaining said car-

65 tridge upon the smooth portion of said rod;

and means whereby said cartridge is in communication with said priming charge and adapted to explode it.

3. In a projectile, a fuse casing; time fuse mechanism in said casing including two

70 shafts, parallel with the axis of the projectile, having means whereby they may be automatically rotated; one of said shafts being screw threaded; a nut on said screw shaft; means preventing the rotation of said

75 nut; an element of pyrographic alloy carried by said nut; a rotary striker wheel carried by said other shaft, in position to scratch said alloy when the latter is presented thereto by the traverse of said nut

80 on said screw shaft; whereby sparks are produced by the engagement of said wheel and allow; a firing train arranged to be ignited by such sparks; a priming charge of explosive in operative rotation to said

85 firing train, arranged to explode the projectile; means whereby the position of said wheel may be variably adjusted including a timing scale frame, mounted in said body, parallel with said shafts, and means for ad-

90 justing said frame longitudinally in said casing; a carriage for said wheel mounted to slide axially upon its shaft; screw means whereby said carriage may be clamped in different positions of adjustment on said

95 frame, to variably determine the point in the traverse of said nut where it shall be engaged by said wheel.

4. In a projectile, a fuse casing; time fuse mechanism in said casing including two

100 shafts, parallel with the axis of the projectile, having means whereby they may be automatically rotated; one of said shafts being screw threaded; a nut on said screw shaft; means preventing the rotation of said

105 nut; an element of igniting material carried by said nut; a rotary striker wheel carried by said other shaft, in position to scratch said igniting material when the latter is presented thereto by the traverse of said nut on said screw shaft; whereby a flash is produced by the engagement of said wheel with said igniting material; a firing train arranged to be ignited by such flash, including a trough shaped metal holder, ex-

110 tends parallel with said shafts and carrying combustible material upon its face toward said wheel; a movable cover for said train; means to move said cover; a priming charge of explosive in communication with

115 said firing train when said cover is removed; arranged to explode the projectile; and means whereby said wheel may be held in variable predetermined longitudinal position on its shaft.

5. In a projectile, a fuse casing comprising a body portion, having a recess; caps respectively at the front and rear of said body; a tubular, shield encircling said body, between said caps, having an opening adapted

120

125

130

- to register with said recess, but rotatable on said body to close said recess; time fuse mechanism in said casing including two shafts, parallel with the axis of the projectile, having means at the front end thereof whereby they may be pneumatically rotated; one of said shafts being screw threaded; a nut on said screw shaft; means preventing the rotation of said nut; an element of pyrographic alloy carried by said nut; a rotary striker wheel carried by said other shaft, in position to scratch said alloy when the latter is presented thereto by the traverse of said nut on said screw shaft; whereby 5 sparks are produced by the engagement of said wheel and alloy; a firing train arranged to be ignited by such sparks, including a holder carrying a strip of combustible material upon its face toward said wheel; a 10 priming charge of explosive at the rear end of said firing train, arranged to explode the projectile; means whereby the position of said wheel may be variably adjusted, including a timing scale frame, mounted in 15 said body, parallel with said shafts, and having a slot, a series of serrations, and means for adjusting said frame longitudinally in said casing, including a screw at one end thereof; a carriage for said wheel 20 mounted to slide axially upon its shaft, having serrations complementary to the serrations on said frame, and a screw threaded shank extending through said slot, and a nut, whereby said carriage may be clamped in different positions of adjustment on said frame, to variably determine the point in the 25 traverse of said nut where it shall be engaged by said wheel.
6. In a projectile, a casing; percussion 30 fuse mechanism in said casing, including a rod, parallel with the axis of the projectile, having one portion smooth and another portion roughened; a cartridge mounted on the smooth portion of said rod, but adapted to 35 slide upon the rough portion of said rod, including an outer metallic shell inclosing an element of pyrographic alloy, and an explosive element arranged to be ignited by sparks 40 from such alloy; means in said casing normally detaining said cartridge upon the smooth portion of said rod, including a frangible projection in said casing engaging the shell of said cartridge; a priming charge; and means whereby said cartridge 45 is in communication with said priming charge and adapted to explode it.
7. In a projectile, a casing; percussion fuse mechanism in said casing including a rod, parallel with the axis of the projectile, having one portion smooth and another portion roughened; a cartridge mounted on the smooth portion of said rod, but adapted to 50 slide upon the rough portion of said rod, including an element of pyrographic alloy, and an explosive element arranged to be ignited 55

by sparks from such alloy; frangible means in said casing normally detaining said cartridge upon the smooth portion of said rod, including a frangible projection in said casing engaging the shell of said cartridge; a 70 priming charge; and means whereby said cartridge is in communication with said priming charge and adapted to explode it.

8. In a projectile, a fuse casing; time fuse mechanism in said casing including two 75 shafts, parallel with the axis of the projectile, having means whereby they may be automatically rotated; one of said shafts being screw threaded; a nut on said screw shaft; means preventing the rotation of said nut; 80 an element of pyrographic alloy carried by said nut; a rotary striker wheel carried by said other shaft, in position to scratch said alloy when the latter is presented thereto by the traverse of said nut on said screw shaft; 85 whereby sparks are produced by the engagement of said wheel and alloy; a pocket carried by said nut containing explosive accessible to said sparks, a chamber, carried by said nut, in communication with said pocket, and 90 a priming charge of explosive in said chamber; and a firing train in co-operative relation with the priming charge carried by said nut.

9. In a projectile, a fuse casing; time fuse 95 mechanism in said casing including two shafts, parallel with the axis of the projectile, having means whereby they may be automatically rotated; one of said shafts being screw threaded; a nut on said screw shaft; means preventing the rotation of said nut; 100 an element of pyrographic alloy carried by said nut; a rotary striker wheel carried by said other shaft, in position to scratch said alloy when the latter is presented thereto by 105 the traverse of said nut on said screw shaft; whereby sparks are produced by the engagement of said wheel and alloy; a pocket carried by said nut containing explosive accessible to said sparks, a chamber, carried by said nut, in communication with said pocket, and 110 a priming charge of explosive in said chamber.

10. In a projectile, a fuse casing; an igniting device; and a firing train adapted to co- 115 operate with said igniting device, including a trough shaped metal holder, carrying combustible material, a movable safety cover for said train, normally sealing said combustible material and preventing communication 120 between said igniting device and said firing train, and means to remove said cover.

11. In a projectile, a fuse casing comprising a body portion of nonmetallic material, having a recess; metallic caps respectively at 125 the front and rear of said body; a tubular, metal shield encircling said body, between said caps, having an opening adapted to register with said recess, but rotatable on said body to close said recess; and adjustable time 130

fuse mechanism in said casing, accessible when the opening in said shield is in registry with said recess.

12. In a projectile, a fuse casing; and time fuse mechanism in said casing including a screw shaft in coaxial relation with said casing, a driving shaft having its axis of rotation parallel with said screw shaft, having a vane whereby it may be pneumatically 5 rotated, worm gearing connecting said

shafts, and an igniting device operatively connected with said screw shaft.

In testimony whereof, I have hereunto signed my name at Philadelphia, Pennsylvania, this ninth day of March, 1918.

JOSEPH A. WALSH.
